UNITED STATES PATENT OFFICE.

BENJAMIN LANDAU, OF PHILADELPHIA, PENNSYLVANIA.

SHOWER-BATH CABINET.

1,392,580.

Specification of Letters Patent. Patented Oct. 4, 1921.

Application filed March 8, 1921. Serial No. 450,516.

To all whom it may concern:

Be it known that I, BENJAMIN LANDAU, a citizen of the United States, and a resident of the city of Philadelphia, in the county 5 of Philadelphia and State of Pennsylvania, have invented certain new and useful Improvements in Shower-Bath Cabinets, of which the following is a specification, reference being had to the accompanying draw- 10 ing.

It is well known that the ordinary fabric curtain suspended from an overhead rod or ring which is frequently utilized to confine the spray of a shower head positioned 15 over an ordinary bath tub is open to numerous objections in that it is frequently not entirely effective to confine the spray or splash, is disagreeable to the touch when wet, and requires to be frequently taken 20 down and laundered in order to maintain it in clean and sanitary condition. In spite of these disadvantages, no satisfactory substitute for the curtain has hitherto been found which is adaptable for use for this 25 purpose.

A principal object of my invention is to provide means in combination with an ordinary bath tub for confining the spray discharged from an overhead shower head 30 which shall be effective for the purpose intended, ornamental, convenient of operation and which will not prevent or interfere with the ordinary use of the tub. Further objects of my invention are to provide means 35 of the character aforesaid which may be readily installed in connection with bath tubs already in position, which are of strong and sturdy construction and not liable to get out of order or be damaged in use.

40 My invention further includes all of the other novel objects and various details of construction and arrangement hereinafter more definitely specified and described.

While for the purpose of accomplishing 45 the objects of my invention I may employ various instrumentalities and combinations thereof effective for obtaining the results desired, I have, to enable those skilled in the art to comprehend and practice the in- 50 vention, illustrated in the accompanying drawing a preferred embodiment thereof showing the same in combination with a bath tub of well known design. In the said drawing Figure 1 is a perspective view of the 55 said form of the invention showing in full lines the position of the main and auxiliary

doors when the cabinet is closed to enable the bath tub to be used in the ordinary manner and in dotted lines the position thereof when the cabinet is open as when the shower 60 is being used, the position of the auxiliary door when opened to permit access to the valves controlling the flow of water to the tub when the main door is closed being also indicated in dotted lines. Fig. 2 is a 65 fragmentary top plan view of the form of the invention shown in Fig. 1.

While the use of the invention is not limited to any particular form or style of tub, it is ordinarily and preferably installed 70 in combination with a tub A of the general character of that shown in the drawing and which is permanently positioned in the angle formed between the walls B, B' of a bath room to rest on the floor C thereof, 75 the walls and floor being conveniently tiled or otherwise treated so as to render them waterproof. Tubs of this general character comprise upper longitudinally extending 80 rims or edges D, D', and for controlling the admission of water to the tub through a spigot E a plurality of taps or faucets F are conveniently arranged so as to extend beyond the face of the wall B adjacent the end of the tub in the ordinary manner. Positioned 85 at a suitable height above that end of the tub adjacent the junction of the walls B, B' is a shower head S to which water is admitted through pipe S', the flow of water thereto being controlled by a plurality of 90 taps F' positioned adjacent the taps F for convenient operation. The arrangement and construction of the several parts to which reference has been made will be 95 readily understood by those familiar with the art.

In installing my improved shower bath cabinet in combination with a tub of the character aforesaid, I position a vertically extending support 2 of marble or other suitable material adjacent the wall B in such position that the lower extremity of the support preferably rests on the rim or edge D of the tub and rigidly secure the support, which forms a jamb for the main door hereinafter described, to the wall B in any suitable manner, as by the angle irons 3, 3 affixed to the support and to the wall. The upper end of the support terminates below, but preferably adjacent the under side of 110 the head S. Hinged to the free vertically extending edge of the support or jamb 2 as

by the hinges 5, 5 is a main door frame 6 which comprises spaced uprights 7, 7' and transversely extending upper and lower cross members 8, 9, the uprights and member 9 being suitably rabbeted or otherwise formed to receive and support a sheet of glass 10 which entirely fills the upper part of the frame but terminates a considerable distance above the transverse member 8.

10. The hinges 5, 5 are preferably so disposed that when the main door is open as indicated in dotted lines in Fig. 1, the face of the upright 7 will abut against the free, vertically extending edge of the jamb 2 preferably for substantially its entire length so as to form a relatively tight closure at this point. The length of the cross members 8, 9 is such that when the door is in closed position, as shown in full lines in Figs. 1 and 2, the outer edge 15 of the upright 7' will rest adjacent the wall B' though preferably slightly out of contact therewith, and a suitable spring catch 12 of any convenient form is arranged to engage the edge of the upright or a spring-pressed ball or the like carried thereby to retain the door in closed position.

It will be understood that the width of the jamb 2 is sufficient to permit the door when closed to lie in a plane somewhat in front 30 of the taps F, F', and for the purpose of giving access to the taps and more especially to those which control the flow of water into the tub through the spigot E, I preferably arrange within the lower part of the main door frame and beneath the glass 10 an auxiliary door 15 which comprises spaced uprights 16, 16' and transversely extending cross members 17 and 18, the upright 16' being hinged to the upright 7' of the main door frame as by the hinges 19 in such manner that the auxiliary door may be swung open relatively to the main door to assume the position indicated in dotted lines in 40 Fig. 1 when the main door is closed, the auxiliary door being thus relatively movable with respect to the main door and also movable therewith. The upright 16 of the auxiliary door is preferably provided with a suitable spring catch 20 of any convenient form adapted to retain the auxiliary door in closed position within the main door, knobs 21 respectively positioned on the uprights 7' and 16 affording convenient means for opening the main and auxiliary doors 50 against the resistance of the spring catches 12 and 20. It will be understood that the auxiliary door frame is rabbeted or otherwise arranged to support a sheet of glass 23 which, when both doors are closed, covers 55 the taps F, F' but lies in a plane somewhat in front of the said taps so as to be out of contact therewith, the height of the auxiliary door being preferably such that the cross member 18 will lie at a suitable distance above the taps and adjacent the lower

edge of the glass 10, thus permitting convenient access to all of the taps when the main door is closed and the auxiliary door opened.

When it is desired to utilize the cabinet 70 for the purpose of confining the spray and splash of the water descending from the shower head S, the main door is swung open to the position indicated in dotted lines in Fig. 1 in which it rests over the edge D of the tub and parallel thereto, the auxiliary door of course being closed. Under these conditions a person standing in the tub beneath the shower head has convenient access to all of the taps while the spray and splash of the water descending from the head is directed into the tub by the doors and the walls B, B'. Ordinarily when the shower is not being used the main door is kept in closed position, and to afford access to the taps F, F' the auxiliary door may either be left normally in open position (as indicated in dotted lines) or opened thereto only when it is desired to reach the taps, the member 8 of course at all times extending transversely across the tub adjacent the spigot E but in nowise interfering with the customary use of the tub.

While I have herein described and illustrated with some particularity a preferred embodiment of my invention in combination with a tub of well known form, I do not thereby desire or intend to limit myself thereby to the precise details of construction and arrangement of parts which I have shown, as the same may be modified and varied in minor particulars in order to adapt the invention for installation under varying conditions and with different forms of tubs without departing from the spirit and scope of the invention as defined in the appended claims.

Having thus described my invention, I claim and desire to protect by Letters Patent of the United States:

1. The combination with a bath tub, of a fixed upright forming a jamb, a door hinged to said upright and movable from a position transverse to and extending over the tub to a position parallel with said upright and with the longitudinal edges of the tub and against said jamb.

2. In combination with a bath tub, a device of the class described comprising a fixed upright forming a jamb, a main door hinged to said upright and movable from a position transverse of said tub to a position substantially parallel with the longitudinal edges thereof and against said jamb, and an auxiliary door hinged within the main door and movable with said main door and relatively to said main door.

3. The combination with a bath tub, of a vertically extending upright rigidly secured adjacent an end of said tub, a door hinged

to said upright and movable from a closed position at right angles thereto to an open position parallel thereto, said upright forming a jamb for the door, and an auxiliary door hinged within said main door adjacent its lower end and movable with said main door and relatively to said main door.

4. The combination with a bath tub, of a vertically extending fixed upright positioned adjacent an end of the tub, a main door frame hinged to said upright, a sheet of glass within the upper part of said frame, an auxiliary door below said glass and within said frame and hinged thereto at the edge 15 of the main frame opposite to that which is hinged to the support, said auxiliary door being movable with said main frame and relatively movable with respect thereto.

5. The combination with a bath tub, of a 20 vertically extending fixed support secured

adjacent one end of the tub, a main door frame hinged at one edge to said support and movable from closed position at right angles thereto to open position substantially parallel therewith, a glass supported within the upper portion of said frame, an auxiliary door frame within said main frame below said glass and hinged to said main frame adjacent the edge thereof which is opposite to that hinged to said support, a 25 glass supported in said auxiliary door frame, and means for maintaining said auxiliary door in closed position within said main door frame, said auxiliary door being movable with said main door frame and 30 relatively to said main door frame.

In witness whereof, I have hereunto set my hand this third day of March, 1921.

BENJAMIN LANDAU.
